No. 36,762.

Patented February 2, 1904.

UNITED STATES PATENT OFFICE.

FRANZ HULD, OF NEW YORK, N. Y.

DESIGN FOR A SOUVENIR CARD OR SIMILAR ARTICLE.

SPECIFICATION forming part of Design No. 36,762, dated February 2, 1904.

Application filed December 18, 1903. Serial No. 185,751. Term of patent 3½ years.

To all whom it may concern:

Be it known that I, FRANZ HULD, a subject of the Emperor of Germany, residing in the city of New York, borough of Manhattan, county and State of New York, have invented a new, original, and ornamental Design for a Souvenir Card or Similar Article, of which the following is a specification.

My new design is represented in the accompanying drawing, forming a part hereof, wherein is shown a face view of a souvenir card embodying my design.

What I claim is—

The ornamental design for a souvenir card or similar article, as herein shown.

FRANZ HULD.
